Primary Examiner — Kimberly Barnes(74) *Attorney, Agent, or Firm* — Reed Smith LLP; Walter M. Egbert, III; Richard J. Brown(57) **CLAIM**

I claim the ornamental design for a unicorn LED helmet, as shown and described.

DESCRIPTION

FIG. 1 is a front, left perspective view of a unicorn LED helmet showing my new design.

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The evenly broken lines in the figures represent portions of the unicorn helmet that form no part of the claimed design.
